UNITED STATES PATENT OFFICE.

WILLIAM S. WESTON, OF DALLAS, TEXAS.

ANTICREEPER FOR RAILWAY RAILS.

Application filed August 28, 1924. Serial No. 734,622.

To all whom it may concern:

Be it known that I, WILLIAM S. WESTON, a citizen of the United States, residing in the city of Dallas, county of Dallas, and State of Texas, have invented certain new and useful Improvements in Anticreepers for Railway Rails, of which the following is a full, clear, and exact description.

My invention relates to an improved form 10 of spring clamp anticreeper, adapted to utilize in functional operation a double or multiple lever grip on the rail base, the initial friction bearings establishing such grip being maintained by the spring relation of 15 the parts. My present invention is distinguished from that set forth in U. S. Letters Patent No. 1,120,258, granted to me December 8, 1914, by providing two or more pairs of seats for the establishment of two 20 or more distinct lever grips and which, in the preferred embodiment of the invention, operate in a vertical plane on one base flange only.

The object of my present invention is an improved 25 anticreeper providing a greater number of distinct effective bearings of a lever grip character established at installation solely by the spring quality of the device, and subsequently utilized in the transmission 30 of the reaction or holding force from the substructure to the rail, and an anti-creeper having in the same construction a wider range of adjustment to the allowable variation in the dimensions of standard railway rail sections. The novel features of 35 construction whereby I attain this object are hereinafter described and fully illustrated in the accompanying drawings, which form a part of these specifications, and are 40 particularly pointed out in the claims.

Referring to the drawings:

Fig. 1 is a side elevation of a rail showing one form of the improved anticreeper in operative position on the base and abutting 45 against the tie or part of the sub-structure.

Fig. 2 is an elevation of the anti-creeper, as seen from the left of Fig. 1, omitting the tie and with the rail shown in cross section.

Fig. 3 is a plan view of Fig. 1.

Fig. 4 is an enlarged vertical section on the line 4-4 of Fig. 2, with a portion of the tie in end view.

Figs. 5 and 6 illustrate the shape of the device as manufactured and before instal-

Figs. 7 to 12 are views corresponding respectively to Figs. 1 to 6, of a modification.

Fig. 13 is a side elevation, and Fig. 14 is a cross section of a modified form embodying a combined rail anchor and tie 60 plate.

Fig. 15 is a vertical section on lines 15-15 of Figs. 14 and 16.

Fig. 16 is a vertical section on lines 16-16 of Figs. 13 and 15. 65

Fig. 17 is a side elevation of the clip shown in Figs. 13 to 16, and illustrating its manufactured shape.

Fig. 18 is a plan of a further modification embodying an anchoring clip and tie plate. 70

Fig. 19 is a plan of the clip alone.

Fig. 20 is a vertical section on lines 20-20 of Figs. 18 and 19.

Fig. 21 is a vertical section on lines 21-21 of Fig. 20. 75

Figs. 22 and 23 are side and end views of the clip alone.

In one of its forms, as illustrated in Figs. 1 to 6, the device is made from rectangular 80 spring steel bent into flange embracing jaws, mounted in close contact with each other on one base flange. Each jaw, composed of top and bottom members, is joined in an integral connection with the contiguous jaw at the end of one member only. In the form illustrated there are three jaws, the first jaw marked A, adjacent the tie T, being connected to the middle jaw B at the ends of their bottom members, and the metal jaw being connected to the third jaw C 85

at the ends of their top members. The bottom member of the third jaw is extended beneath the rail R to form the transverse bar F, which is provided at the end with a shoulder S for bearing against 90 the edge of the opposite base flange. As will be described, the transverse bar F is held up against the base of the rail so that the shoulder S in turn prevents the jaws from working off the opposite flange, not by means of the third jaw, of which the transverse bar is the bottom member, but by means of its spring relation to the other jaws through their integral connection. 95

Before explaining the mechanical relation of the jaws at installation and during functional operation, it is important to note that each jaw in itself in respect to the angle between its members is made as rigid and inyielding as possible. For a lever grip 100

110

each jaw having one bearing on the top of the rail base and one on the bottom, acting as fulcrums, is dependent on the unyielding relation of its members for effective functional operation. The individual jaws are therefore made slightly larger than the thickest flange on which they are to be mounted, the jaw having the transverse bar with the shoulder S being made enough 10 larger to permit the shoulder to come clear without any expansion between the bar member and its respective top member. The jaws are therefore preferably made by bending the steel stock edgewise, as shown, 15 with the members extending only a relatively short distance under and over the rail base flange, as compared with the total rail base width.

In the manufactured form of the device, 20 Figs. 5 and 6 starting with the rail seating space in the jaw C and the transverse bar in normal horizontal position, the other jaws have been rotated upward in their integral connections so that the bottom of the middle 25 jaw B is a measurable distance above the position required by the rail base to be passed through jaw C, and the bottom of jaw A substantially double that distance above jaw C. The relative rotation of the 30 jaws is such that the clear space through them for the edge of the rail base is considerably thinner than required by the rail on which it is to be used. This fact is indicated in Fig. 5 by the dotted outline of 35 the edge of a base flange drawn in the general direction of the space at the bottom of the jaws, also shown by dotted outline. It will be evident now that to mount the device on a rail base on which each jaw of it- 40 self is designed to fit readily, jaws A and B must be sprung downward in their relation to jaw C against the resilient quality of the integral connections between the jaws. To repeat substantially the wording of the 45 prior patent mentioned above, the anticreeper is made of resilient material on a form somewhat smaller, taken as a whole, than the base of a rail onto which it is to be sprung by force in the process of in- 50 stallation.

The process of installation will be understood by referring to Fig. 6, which illustrates, with a rail base shown in dotted outline, the initial position in which the 55 anticreeper is placed by hand. Hammer blows are then applied to jaw A in the direction indicated by the arrow 24, rotating both jaws A and B downwardly and moving all three jaws further on to the base 60 until the shoulder S comes into the clear and the device takes the position of Fig. 2. The recoil from the downward spring of the jaws A and B tends to restore them to the relative shape shown in Fig. 6. An im- 65 mediate effect of the recoil tendency with

jaws A and B held down by the rail flange is to hold the transverse bar member of jaw C snug against the rail base, thereby holding the retaining shoulder S in position, as stated above. Another effect of the recoil is to cause the jaws to take the position illustrated on a larger scale in Fig. 4 with the jaws returned a small amount toward their manufactured relation, depending upon how much larger each jaw may be 70 than the flange on which it is mounted and upon how much the points of bearing have bitten into the rust and scale of the rail. The result is that each jaw has two distinct points of bearing, one on the top and 75 one on the bottom of the flange in diagonal relation to each other. These points, marked a^1 and a^2 for jaw A, b^1 and b^2 of jaw B, and c^1 and c^2 for jaw C, are thus established at installation as the fulcrums of 80 lever grips operating in a vertical plane.

The functional operation is as follows: If the rail R tends to creep toward the left, the tie reaction force, indicated by the arrow 25, takes effect on the lower member of 90 jaw A tending to rotate it counter-clockwise, as viewed in Fig. 4, bringing into effect bearings a^1 and a^2 as fulcrums of a lever grip. As soon as the reaction force is great enough to cause these bearings of jaw A to move or bite still deeper into the rust and scale, it will be transmitted by direct contact to the lower member of jaw B, which in turn by means of its bearings b^1 and b^2 becomes the medium of a second lever grip. 95 A still greater force and a movement of jaw B would then by its direct contact bring jaw C into action.

By the functional action just described, 100 operating through a multiple lever grip established on the rail base in the process of installation, the reaction force is distributed and delivered to the rail through a multiple of effective bearings. It should be noted here that I do not limit myself to the use 105 of the exact number of three jaws, arranged in close contact and functioning in the manner just described. I might use more than three jaws or only two. Another jaw between jaw A and the tie manufactured still 110 further upward might be added, or jaw A might be removed without changing the mechanical relation and operation of the parts.

The form of anticreeper illustrated in 115 Figs. 7 to 12 follows the general lines of the device covered by the prior patent above mentioned. My present improvement is embodied in a change in the exact shape and 120 relation of the parts whereby I can utilize a double lever grip operating in a vertical plane on one base flange only.

In this form of the anticreeper, as in the 125 prior device, there are three distinct bearings on the rail base flanges, two flange em- 130

bracing jaw bearings A' and B', on one flange, and one shoulder bearing S' on the opposite flange. The single bearing S' is connected with the bearing B', on the opposite flange, which is the farther from the tie, by means of a transverse bar F', located beneath the rail base, while the two bearings A', B', on the same flange are connected by means of a bar L, located longitudinally with the rail and above the top surface of the flange. The bearing A' supports a tie-abutting pendant P. My present improvement is embodied in the exact form and relation of the two bearings A' and B' and the longitudinal bar L. This bar is positioned more nearly parallel with the rail and connected at the rear end with the transverse bar in such manner that the bearing B' is more positively a flange embracing jaw than in the prior device. Also the forward end of the longitudinal bar where it is bent downwardly to form the tie-abutting pendant is shaped in such manner that the bearing A' is a flange embracing jaw. These flange embracing jaws are each made larger than the thickest rail flange on which they are to be used and in this respect provide for an adjustment to a variable thickness of flange, as in my prior patent.

A novel feature of my present form of anticreeper with the three points of bearing on the rail is embodied in the shape of the longitudinal bar which is manufactured with the center bent upwardly so as to draw the bottom members of jaws A' and B' toward each other and give before installation a continuous space through the two jaws that is thinner than the thinnest rail flange on which the device is to be used. This construction is indicated in Fig. 11, in which the relation of the continuous edge of the rail flange and the bottoms of the jaws is indicated by dotted outline.

At installation the device is first placed on the rail base by hand in the position of Fig. 12. It is then driven by hammer blows applied as indicated by the arrow 26, bringing bearings A' and B' to their seat and bearing S' in the clear and to its seat, the device taking the position of Fig. 8. In the installation process the longitudinal bar is sprung sufficiently straighter than manufactured to permit the adjustment of the jaw seats A' and B' to the thickness of the flange on which they are mounted, as indicated in Fig. 10. The internal strain in the longitudinal bar thus straightened causes jaws A' and B' each to take bearings on the top and bottom surfaces of the flange at points a^3 , a^4 and b^3 , b^4 respectively, which tend to bite into the rust and scale and which are thus established as the fulcrums of lever grips effective in functional operation.

The tendency of the device to move to the left is met by a tie reaction force indicated by the arrow 25, taking effect on the tie-abutting pendant, tending to rotate the jaw A' counter clockwise and utilizing a lever grip in a vertical plane with bearings a^3 , a^4 , acting as the fulcrums. As the reaction force increases sufficiently to cause the bearings to bite deeper into the rail and allow jaw A' to move slightly along the rail, the reaction force will be transmitted to jaw B' through the longitudinal member in the direction indicated by arrow 27, tending to rotate that jaw in the opposite direction or clockwise, a tendency which it already has because of the internal strain in the longitudinal member, utilizing a second lever grip in a vertical plane with bearing b^3 , b^4 , acting as the fulcrums. A double lever grip operating in a vertical plane on one base flange is thus provided and the reaction force distributed and delivered to the rail in this form through four effective bearings. Because both jaws are held to their bearings by the reaction of the initial strain developed at installation in the longitudinal bar L, the transverse bar F' which is the extension of the bottom member of jaw B', will be held snug against the base of the rail with the shoulder S' in position to take a bearing against the rail base edge and prevent the jaws from backing off the flange. It will be noted that in both of the forms of anticreeper described, the tendency in functional operation is to restore it to its manufactured shape and that the principal strains of installation are therefore relieved rather than increased. The result is that up to the point where the manufactured shape may be fully restored, the internal strains of installation will take up and hold the bite of the bearings and retain the anticreeper in operative position.

In the foregoing description the shoulder bearing S on the end of the transverse bar was considered solely as means for preventing the jaws on the opposite flange from working off in the direction opposite to that of installation. It will be obvious, however, that in the event the multiple jaws on the opposite flange should be moved along the rail by a heavy reaction force, and there should be any friction whatever at the time in the bearing of shoulder S or S' holding it in place, that the transverse bar would tend to rotate in a horizontal plane. That would develop a lever grip in that plane with bearing S' and the bottom of jaw B' of the form of Fig. 9, or bearing S and the bottom of jaw C, of the form of Fig. 3, taking seats on opposite flange edges acting as the fulcrums. However, with two or more co-operating vertical lever grips established on one base flange, the development of the horizontal grip just described is not vital to the operation of the device.

It is also to be noted that since the horizontal grip is not vital, the distance between bearing S and the line through the bottom of the jaws on the opposite flange may be 5 made great enough to provide for the allowable variation in the rail base widths or any specified rail section as it comes from the rolling mill. That this is practicable will be recognized by considering that in case 10 the anticreeper is mounted on a rail of the minimum allowable width of base and the jaws back off as much as the difference between the maximum and minimum width, the action in effect is only what would happen if the jaws were mounted on a thinner flange. Such a contingency has been provided for as described by the manufactured 15 resilient relation of the jaws.

Referring to Figs. 13 to 17, illustrating 20 the adaptation of my improved anticreeper for use in combination with a tie plate. In this combination the tie plate T' is made to serve the purpose of the transverse bar necessary in the forms already described for preventing the flange embracing jaws working 25 off the rail. The transverse bar is therefore left off, and the anti-creeper clip is held on the flange preferably by means of a hook K, formed on the plate and bearing against 30 the anticreeper, this hook in turn being held to that contact by means of a shoulder S² on the plate that takes a bearing against the opposite rail base flange. The anticreeper clip is located in and above the hole in the 35 plate left by the formation of the hook and in functional operation takes a bearing on one side or the other of that hole. If desired, the hook K could be omitted and the opening in the tie plate so arranged that its 40 outer edge would serve to hold the clip in operative position on the rail. Fig. 16 is a partial cross section on a larger scale transverse to the rail and through the middle of the plate and clip, on the lines 16—16 45 of Figs. 13 and 15. Fig. 15 is a vertical longitudinal section on the line 15—15 of Figs. 14 and 16. Fig. 17 is an elevation of the clip alone as it would be seen from the right of Fig. 16 in its manufactured shape 50 before installation.

In this adaptation the anticreeper clip is made in the shape of two flange embracing jaws A' and B' that are connected through 55 their top members by a bar or plate L', this bar being curved upwardly so as to draw the bottom members of the jaws toward each other, making the continuous space through them less than the thickness of the rail flange, as indicated by the dotted outline in 60 Fig. 17, and in the same manner as in the form previously described and illustrated in Figs. 7 to 12. The top and bottom members of each jaw are spaced to permit it being mounted without material internal strain on 65 the thickest flange with which the device

is designed to be used. Because of this clearance, the connection between the members of each jaw can be and is made as rigid and unyielding as possible, so that, in functional operation, the reaction force 70 may be transmitted through the connection between the jaw members with a minimum of distortion of the jaw itself. On the other hand, the connection between the jaws is made as resilient and flexible as possible 75 to permit the mounting of the device upon the rail base.

At installation, the resilient bar or plate L' is so flattened or strained as to rotate 80 the jaws and bring the flange spaces in line and permit the ready mounting of the device in operative position, as shown in Figs. 15 and 16. The recoil of the plate L' tends to rotate the jaws back to their initial 85 relation, as shown in Fig. 17, and thereby establishes a double lever grip, jaw A' and its bearings a³ and a⁴ providing a lever grip in one direction, and jaw B' and its bearings b³ and b⁴ providing a lever grip 90 in the other direction. The full lever grip thus established and maintained is utilized in functional operation as hereinafter set forth.

At installation the anticreeper is first 95 placed on the rail above the tie. The tie plate is then passed under the rail from that side until the hook and shoulder are brought to their bearings, as shown in Fig. 14. The plate is then spiked or otherwise fastened 100 to the tie.

In functional operation, if the rail tends 105 to move toward the left, as viewed in Fig. 15, the lower member of jaw A' comes in contact with the edge of the hole in the plate so that the tie reaction force is delivered to it in the direction indicated by the arrow 25 and eventually lever grips, one in jaw A' and one in jaw B' are utilized as described for the form of Fig. 10. It is to be noted especially that if the rail tends to move toward the right, bringing the bottom member of jaw B' in contact with the edge of the hole in the plate on that side, the tie reaction force will then be delivered to it in direction indicated by the arrow 28. For 110 movement in this direction, a double lever grip is eventually utilized with the grip of jaw B' coming into effect first.

Figs. 18 to 23 illustrate an alternate construction of the clip for use with a tie plate. 120 In this form, the clip is made of a series of flange embracing jaws A, B, C, D, set with their bottom members in close contact with each other, and with the ends of the top members joined in integral connection by a bar L² across the ends. In the manufactured shape, as illustrated in Figs. 22 and 23, the jaws have been rocked relative to each other by a twist in their connection through bar 125 L², so that the continuous space for the 130

flange is less than the thickness of the flange on which the clip is to be mounted. When driven on the rail each jaw will have bearings on the bottom and top surface of the flange of the same character and serving the same purpose as the jaws described and illustrated in Fig. 4.

In functional operation the tie reaction force, with the rail tending to move toward the left, as viewed in Fig. 21, takes effect on jaw A, as indicated by the arrow 25, utilizing finally the multiple grip described for Fig. 4.

It will be noted at once that the form of Fig. 21 is not operative in both directions. Should the rail tend to move toward the right, a tie reaction force taking effect on the bottom member of jaw C, as indicated by the arrow 29, would tend to rotate the jaws so as to increase the continuous flange space and eventually loosen the grip of each jaw, the jaws as already described being made each with their respective top and bottom members slightly farther apart than required by the thickest flange on which the clip is to be used.

Referring again to Figs. 16 and 20, the top and bottom members of the jaws are preferably made relatively short compared with the width of the rail base, as already specified. The connection between the top and bottom members around the edge of the rail flange is made as heavy and unyielding as possible, so that the strain of installation will be concentrated in and near the integral connection between the jaws, this connection, on the contrary, as already stated, being made as resilient and flexible as possible.

Attention is called to the fact that although the expression "flange embracing jaw" has been used throughout the foregoing description, yet a device embodying the fundamental features of my present invention might be described without the use of that expression and the conception involved. Referring more particularly to the preferred forms shown in Figs. 8 to 17 inclusive, the anticreeper device for preventing the creeping of railway rails, adapted to hold the rails through the medium of a double lever grip, established on one rail base flange, may be described as follows: The device comprises a bar or plate made of resilient material, to be located, when placed on the rail, above the top surface of one flange adjacent and substantially parallel to the edge thereof, the central portion being bent upwardly so that its ends only have bearings on the top surface of the rail flange; in combination with hooks made as rigid and unyielding as possible, attached to the ends of the bar, each in a manner to overhang the edge of the rail flange and take a bearing on the under surface of that flange; the continuous clear space between the bearings of the plate

and the bearings of the hooks being manufactured less than required by the rail flange on which the device is to be used; this space being adapted to be increased the necessary amount to receive the flange by springing 70 downwardly the central portion of the bar. The internal strain thus developed holds the bearings in operative position and these bearings, because of their relative position, are established as the fulcrums of a double 75 lever grip. I, therefore, do not limit my claims for a device providing a double or multiple lever grip on the rail base to a construction involving the specific combination of two or more flange embracing jaws; 80 but claim broadly the construction providing four or more bearings on the rail base arranged in pairs with a relatively rigid connection between the bearings of each pair and a relatively resilient connection between the pairs; whereby because of said rigid connection each pair of the bearings becomes the medium of a lever grip operating in a vertical plane, and whereby because of said resilient connection the pairs of 85 bearings are retained in operative position.

An important feature of the present rail anchor having a multiple lever grip on the rail base, and one which more clearly distinguishes it as an improvement on the prior art is especially to be noted. The construction is such that the resilient connection or connections between the pairs of seats or jaws is strained on installation and tends to rotate each jaw or pair of seats to establish an initial lever grip and the construction is such that, in functional operation, the reaction force tends to rotate each jaw or pair of seats in the same direction to increase the pressure and bite of the lever grip thus initially established. Then this increase in the bite, or more specifically this closer adjustment of the two seats of each pair, is fully retained by the spring clamp 100 quality provided in the combination of relatively rigid and resilient parts in the construction as described. The reliability of the multiple lever grip established at installation is thus increased and insured by 105 the functional operation.

It is also noted that the jaws or pair of seats providing the separate lever grips are relatively disposed one in advance of the other longitudinally of the rail and act consecutively and cumulatively in resisting the creeping of the rail. Changes may be made in the details set forth without departure from the scope of the appended claims.

I claim as my invention:

1. An anticreeper for railway rails having four or more seats for bearing on one base flange, said seats being connected in pairs with the seats of each pair adapted 120 to take bearings on the top and bottom sur-

faces respectively of the base flange and, in functional operation, act as the fulcrums of a lever grip operating in a vertical plane, and said pairs of seats being joined together by a relatively yielding resilient connection or connections adapted, in installation, to establish and maintain the said lever grip of each of said pairs of seats.

2. An anticreeper for railway rails having four or more seats for bearing on one base flange, said seats being rigidly connected in pairs with one seat of each pair adapted to take bearings on the top and bottom surfaces respectively of the base flange, and, in functional operation, act as the fulcrums of a lever grip operating in a vertical plane, said pairs of seats being joined together by a relatively yielding resilient connection or connections adapted, on installation, to establish and maintain the said lever grip of each of said pairs of seats, and means for retaining the anticreeper in operative position on the base flange.

3. An anticreeper for railway rails having four or more seats for bearing on one base flange, said seats being rigidly connected in pairs with the seats of each pair adapted to take bearings on the top and bottom surfaces respectively of the base flange and, in functional operation, act as the fulcrums of a lever grip operating in a vertical plane, said pairs of seats being joined together by a relatively yielding resilient connection or connections adapted, on installation, to establish and maintain the said lever grip of each of said pairs of seats, and means for retaining the anticreeper in operative position, comprising a transverse bar having a shoulder for bearing against the edge of the opposite base flange.

4. An anti-creeper for railway rails comprising two or more jaws arranged to embrace one base flange and having relatively unyielding connections between their top and bottom members, said jaws being joined by an integral resilient connection tending, on installation, to rotate said jaws and hold the members thereof to bearings on the flange that act as the fulcrums of vertical plane lever grips, the pressure or bite of each of which is increased in functional operation by the pressure of the anchor against the substructure.

5. An anticreeper for railway rails comprising two or more jaws arranged to embrace one base flange and having relatively unyielding connections between their top and bottom members, and each having a flange space slightly larger than the rail base flange on which it is to be used, said jaws being joined together by a yielding resilient connection or connections, adapted to be strained on installation and by which the top and bottom members of each jaw are held to bearings that act as the fulcrums

of lever grips operating in a vertical plane.

6. An anticreeper for railway rails comprising two or more jaws arranged to embrace one base flange and having relatively unyielding connections between their top and bottom members, said jaws being joined together by a yielding resilient connection or connections by which the top and bottom members of each jaw are held to bearings that act as the fulcrums of lever grips operating in a vertical plane and the pressure of each of which is increased in functional operation, and means effective in a horizontal direction transverse to said base flange for retaining the anticreeper in operative position.

7. An anticreeper for railway rails comprising two or more jaws arranged to embrace one base flange and having relatively unyielding connections between their top and bottom members, said jaws being joined together by a yielding resilient connection or connections by which the top and bottom members of each of said jaws are held to bearings that act as the fulcrums of lever grips operating in a vertical plane and the pressure of each of which is increased in functional operation, the bottom member of one of said jaws being extended and provided with a shoulder adapted to take a bearing against the edge of the opposite base flange and thereby retain the anticreeper in operative position.

8. A one-piece rail anchor comprising two jaws, both arranged to embrace the same base flange and having relatively rigid connections between their top and bottom members, and a relatively yielding resilient connection between the top members of said jaws holding the same in spaced relation longitudinally of the rail and, on installation, tending to rotate said jaws in opposite directions and thereby initially establish vertical plane lever grips on the base flange, the bite of each of which is increased in functional operation by the pressure applied to the bottom member of one of said jaws.

9. A one-piece rail anchor, comprising a series of two or more substantially rigid jaws having, in operation, vertical plane lever grips on the same base flange of the rail, the said jaws being joined by a relatively yielding connection or connections adapted to be strained on installation and thereby initially establish the said lever grip of each jaw on the base flange.

10. A one-piece rail anchor, comprising a series of two or more substantially rigid jaws having, in operation, vertical plane lever grips on the same base flange of the rail, the said jaws being joined by a relatively yielding connection or connections adapted to be strained on installation and thereby initially establish the said lever grip of each jaw on the base flange, the jaw at

one end of the series having a tie-abutting portion and the lower member of the jaw at the other end of the series having an extension provided with a shoulder for engaging the edge of the opposite base flange.

11. A rail anchor having at least four distinct rail base engaging seats connected in pairs and relatively disposed in order longitudinally of the rail, and a resilient connection between the pairs that is adapted to be strained at installation and thereby tend to rotate each pair of seats and initially establish the lever grip thereof upon the rail base, the rail anchor having a portion adapted to abut against the substructure and thereby increase the pressure of each of the lever grips thus established.

12. A rail anchor having at least four distinct rail base engaging seats rigidly connected in pairs and relatively disposed in order longitudinally of the rail, and a relatively resilient connection between the pairs, said connection being adapted to be strained on installation and thereby tend to rotate each pair of seats and establish the lever grip thereof upon the rail base, the rail anchor having a portion adapted to abut against the substructure and thereby, in functional operation, increase the pressure of each of said lever grips.

13. A rail anchor comprising two substantially rigid jaws relatively disposed in order longitudinally of the rail, and each having a

rail base seating space slightly larger than the rail base to which it is applied and each having, in operation, a lever grip upon the rail base, and an integral resilient connection between said jaws normally holding the same in position to provide a continuous seating space smaller than the rail base, whereby said resilient connection is strained on installation, the construction being such that the reaction force developed in operation and the reaction of said resilient connection act cumulatively in establishing and maintaining the lever grip of each of said jaws upon the rail base.

14. A rail anchor having two substantially rigid jaws relatively disposed in order longitudinally of the rail when mounted thereon, each jaw having rail base engaging edges or seats forming the fulcrums or bearings of a lever grip of the jaw upon the rail base and an integral resilient connection between the jaws adapted to be strained on installation and force the said bearing edges or seats into gripping engagement with the rail base and thereby establish and maintain the said lever grip of each jaw, one of the members of one of said jaws having a portion adapted to abut against the substructure and thereby, in functional operation, utilize the lever grips of said jaws as so established and maintained.

WILLIAM S. WESTON.
